UNITED STATES PATENT OFFICE.

CLARENCE E. LOMAX, OF CHICAGO, ILLINOIS, ASSIGNOR TO AUTOMATIC ELECTRIC COMPANY, OF CHICAGO, ILLINOIS, A CORPORATION OF ILLINOIS.

WIRE CHIEF'S TEST CIRCUIT FOR TELEPHONE SYSTEMS.

Application filed May 18, 1921. Serial No. 470,537.

To all whom it may concern:

Be it known that I, CLARENCE E. LOMAX, a citizen of the United States of America, and a resident of Chicago, Cook county, 5 and State of Illinois, have invented certain new and useful Improvements in Wire Chiefs' Test Circuits for Telephone Systems, of which the following is a specification:

10 The present invention relates in general to wire chiefs' test circuits for telephone systems, but more especially to test circuits of this kind which are adapted for use in automatic telephone systems; and the object of the invention briefly stated is to revise and refine the various circuits used so as to make them more efficient and practical. The apparatus employed and the various features of the invention will be described fully hereinafter, reference being had to the accompanying drawings, in which the system is illustrated by means of the usual circuit diagrams.

Before taking up the drawings in detail, 25 a few general statements, relating to the system as a whole, will be made. Although the features of the invention are applicable to systems of different sizes, it is assumed that we are dealing with a 100,000 line system, which is divided into ten separate main offices of 10,000 lines each, the separate offices being so interconnected with trunk lines as to form an integral system. The testing 30 of the lines in the various offices is assumed to be done from one point by one or more wire chiefs. There are ten separate groups of trunk lines, all groups being multiplied between the wire chiefs' desks, and each group extending to a different main office. 35 Each wire chief, therefore, may obtain direct access with any one of the said main offices, merely by selecting a trunk line in the proper group.

Referring now to the drawings, in order 40 to enable the circuits to be readily understood, Figs. 1, 2 and 3 should be arranged in order, with the corresponding lines at the ends thereof in alignment, and Fig. 4 should be placed directly under Fig. 1. 45 When laid out in this manner, Figs. 1 to 3, inclusive, show all the equipment necessary for a complete connection from the

wire chief's desk to a subscriber's line which it is desired to test. Fig. 4 shows some of the equipment at the complaint or verification operator's position, by means of which the complaint operator can obtain access to the test switches such as are shown in Figs. 2 and 3.

Considering first the means by which the wire chief extends a connection to a subscriber's line, the outgoing trunk line shown terminates at the wire chief's desk in the key K, Fig. 1, to which the wire chief's common test and operating circuits are multiplied. This trunk line terminates at the other end in the switch E, termed a test distributor, which is located in one of the main offices of the system. The test distributor E is a vertical and rotary switch of the well-known Strowger type having 100 sets of bank contacts arranged in ten horizontal rows, or levels. The circuits of this switch are shown complete and will be described in full hereinafter.

The test connector selector F, Fig. 3, is a switch of the Strowger type also, but differs from the test distributor E particularly in having only a single level of bank contacts. It will be understood from this that the switch has a rotary movement only and that the vertical magnet and those parts which have to do only with the vertical movement of the switch may be omitted. It may be mentioned also that the off normal contacts 122 are arranged so as to close on the first rotary step of the switch rather than on the vertical step as is usually the case.

The test connector H is also a Strowger vertical and rotary switch. It has the full 100 contact sets and so far as its mechanical construction is concerned is similar to the test distributor E.

It will be understood that the subscribers' lines in the system are divided into groups of 100 lines each, in accordance with the capacity of the connector switches which are ordinarily used for completing local connections. In every 100 line unit, in addition to the 10 or 12 local connectors which are ordinarily provided, there is one test connector such as the test connector H, the latter connector switch being exclusively for

the use of a wire chief or a complaint operator in testing the subscribers' lines. One of the subscribers' lines of the group to which the connector H belongs, is shown 5 at the extreme right of Fig. 3, and extends to the automatic telephone substation A.

The reference character C indicates an individual line switch of the well known rotary type, which is provided for the use 10 of the subscriber at substation A in extending his line, when calling, to an idle first selector switch in the regular exchange trunking system.

The arrangement of the trunking between 15 the test switches will now be explained a little more fully. Considering a fully equipped office of 10,000 lines capacity, there are 100 groups of connector switches and as a test connector is provided in each of these 20 groups, there are 100 test connectors. Now, since the test distributors have 100 contact sets and are directly controlled in both their vertical and rotary movements, all of these test connectors may be reached by way 25 of the test distributors in the particular office under consideration without any intervening switches. There will be perhaps three or four of these test distributors, such as the test distributor E, Fig. 2 which have 30 common access to all of the test connectors in the office. This is the usual arrangement for a straight 10,000 line office or exchange.

It happens quite often, however, that, in offices which include a number of party 35 lines, in addition to the individual or private lines, fourth selectors are inserted between the third selectors and connectors in those major groups which are used for the party line traffic. This is especially true of systems in which a plurality of groups of connectors, each of which sends out ringing 40 current of a different character, have access to the same 100 lines. In such cases, in order not to reduce the capacity, the party 45 line subscribers are called by means of six digits instead of five, the extra digit being the fourth which controls the operation of the fourth selectors in selecting the proper group of connectors. The drawings show 50 an arrangement of test switches which is adapted for use in a composite office of the type described which includes both individual and party lines. The test distributors have direct access to all of the test connectors 55 which are located in the individual line connector groups, but on the particular level, or possibly levels, which are assigned to the party lines, the test distributors have access to test connector selectors such as the test connector selector F, which is shown in Fig. 60 3. Each connector selector in turn has access to the test connectors in ten different connector groups.

Considering now the means by which the 65 complaint, or verification operator extends

a connection to a subscriber's line, the trunk line comprising conductors 250 and 251, which may be one of a group sufficient in number to handle the traffic, extends from the connecting key K⁷, in the office in which the complaint operator is located, to the test distributor selector repeater D, in the office in which the wire chiefs are located. Mechanically the switch D is the same as the switch E or the switch H. The circuit of 75 the switch D, however, differs from either of these as will be pointed out fully hereinafter.

The switch D, with regard to the trunking arrangement, plays the part of a first selector and accordingly trunk lines, of which the trunk line comprising conductors 32-36, inclusive is one, extending to a main office or exchange, are terminated in each level of bank contacts, according to the usual practice. 80

The system, having been described generally, will now be described in connection with a detailed explanation of the operation of the various circuits. For this purpose it 85 will be assumed that the wire chief wishes to test the line of substation A. It is first necessary for the wire chief to obtain connection with a test distributor in the particular office in which the line of substation A 90 terminates. To do this he operates a key which is associated with a trunk line extending to the particular main office in which the line of substation A terminates, the key K³, for example, the associated trunk line being 95 idle as indicated by the unlighted condition of busy lamp L². Upon operating, the key K³ places ground on the conductor 36 at spring 39, thereby lighting busy lamps before the other wire chiefs. This ground potential extends by way of conductor 36 to test contact 247, Figure 4, and its multiples in the banks of the test distributor selector repeaters thereby guarding the seized trunk line against intrusion in the usual manner. 100 As a further result of the operation of key K³, it connects the wire chiefs' test conductors 30 and 31 in multiple with the test conductors 32 and 33 of the trunk line associated with the key K³, by way of the working contacts of springs 15 and 18 of said springs, resting contacts of armatures 21 and 23 and said armatures; and closes a circuit for the polarizing winding of electropolarized relay 110 7 at spring 13. Relay 7 is not operatively 115 energized at this time, however, owing to the fact that the flux that is generated in the right hand core is shunted away from the armature and heel piece by the left hand core. As a further result at the operation of key K³, the springs 14 and 19 place the following bridge across the operating trunk conductors 34 and 35: from conductor 35, by 120 way of spring 19 and its working contact, spring 5 of key K⁷ and its resting contact, 125

130

normally closed contacts controlled by spring 3 of key K, spring 4 of the same key and its resting contact, normally closed contacts controlled by spring 2 resting contact of spring 6 of key K' and the said spring, left hand winding of electropolarized relay 7, and the working contact of spring 14 of key K³ and said spring, to conductor 34. Conductors 34 and 35 terminate in the upper and lower windings of line relay 43 of test distributor E, passing through relays 41 and 42. Accordingly, the said relays 41 to 43, inclusive, energize.

Electropolarized relay 7, however, is not energized, at this time, because the flux generated in the left hand winding coincides in direction with the flux formerly shunted from the armature by the core associated with the said winding. Each core now acts 20 a magnetic short circuit for the flux generated in the other.

Returning now to the line relay 43 of the test distributor E, upon energizing, the said relay closes a circuit for release relay 44 which, upon energizing, opens a point in the circuit of release magnet 64 at armature 62, at the same time preparing a circuit for the vertical magnet 99.

The wire chief now throws his key K in such a direction as to operate the springs 2 and 3, thereby inserting his calling device and head set into the control circuit.

The wire chief may now manipulate the dial of his calling device in accordance with the first digit of the desired number, whereupon the line relay 43 is deenergized a corresponding number of times and, upon each deenergization, closes the following circuit: from ground, by way of armature 60 and its resting contact, armature 62 and its working contact, off normal springs 70 and 68, slow acting series relay 45, and vertical magnet 99, to battery. By the operation of the vertical magnet, the shaft and wipers are raised 45 step by step until the latter stand opposite the desired level of bank contacts. The slow acting relay 45 is energized in series with the vertical magnet and at its armature 63 maintains the circuit of the vertical magnet intact after the off normal springs have shifted as they do upon the first vertical step. At the end of the vertical movement, slow acting relay 45 deenergizes and transfers the impulsing circuit from the vertical 50 to the rotary magnet.

The wire chief now turns the dial of his calling device for the second digit whereupon the line relay 43 is deenergized a corresponding number of times and at each de-energization completes the following circuit: from ground, by way of armature 60 and its resting contact, armature 62 and its working contact, off normal springs 70 and 69, armature 63 and its resting contact, and slow acting relay 46, to battery. A branch

of this circuit extends by way of armature 77 and its resting contact, armature 82 and its resting contact, and rotary magnet 100 to battery. By the operation of the rotary magnet, the shaft and wipers are rotated 70 step by step until the latter finally come to rest on the desired set of contacts, assumed in this case to be the contacts 93 to 98, inclusive. The slow acting relay 46 is energized in multiple with the rotary magnet and at 75 armature 72 closes the following circuit for the slow acting relay 47: from ground, by way of working contact of armature 61 and said armature, resting contact of armature 79 and said armature, armature 72 and its 80 working contact, and slow acting relay 47, to battery. Upon energizing, relay 47 closes a busy test circuit at armature 75 and at armatures 85 and 86 opens the heavy test conductors so as to prevent interference with 85 the trunk lines over which the wipers pass.

At the end of the rotary movement the slow acting relay 46 deenergizes and at armature 72 opens the circuit of relay 47 and at the same time completes a circuit for 90 switching relay 49 by way of the working contact of armature 76 and said armature, and switching relay 49 to battery. Switching relay 49, on account of its inductive winding and stiff adjustment is slightly 95 reluctant in energizing. The operation now depends upon whether the test contact 96 with which the test wiper 90 is in engagement is busy or idle. If it is busy it has a ground potential on it and a circuit is closed 100 from ground by way of the said test contact, test wiper 90, armature 83 and its resting contact, armature 75 and its working contact, upper winding of busy relay 48, and relay 47 to battery. Relay 48 is energized 105 over this circuit and relay 47 is maintained energized. Upon energizing, relay 48 opens the circuit of switching relay 49, at armature 79, before the said relay has had time to energize; connects, at armature 80, a lead from the busy signalling machine B to the lower operating conductor 35, thus giving the wire chief an audible busy signal; and at armature 78 closes the circuit of reversing relay 40. Upon energizing, relay 40 reverses the 110 operating conductors 34 and 35 as regards their connection with line relay 43. This obviously reverses the direction of current flow in the said conductors and in the left hand winding of the electropolarized relay 115 7 included in a bridge of the said conductors. Heretofore the magnetic flux set up by the left-hand winding of relay 7 has been in such a direction as to coincide with that set up by the right hand winding of the said 120 relay and accordingly the flux was short circuited, so to speak, as none of it was forced to flow out through the heel piece and armature of the relay but rather flowed through the two cores and associated yoke in 125 130

series. At this time, however, the flux produced by the left hand winding of the relay opposes that produced by the right hand winding; thus forcing it to pass out through the heel piece and armature and return through the two cores in parallel. The armature of relay 7 is now attracted and closes a circuit for the busy lamp L^4 which upon becoming lighted, gives the wire chief a visual busy signal in addition to the audible one just described.

Upon learning that the called trunk is busy, the wire chief, if he desires to hold up the connection and wait for the called trunk to become idle, and if he has other duties to perform at this time, may return the key K in vice and head set from the operating circuit, after which he may proceed to perform his other duties.

We shall now assume that the called trunk becomes idle, in which case ground is removed from test contact 96. The circuit of relays 47 and 48 is now open and relay 48 de-energizes. Relay 47, however, being slow to fall-back retains its armatures in the circuit of both the reversing relay 40 at armature 78, and at armature 79 closes the circuit of switching relay 49. Upon energizing, relay 49 closes a locking circuit for itself, at armature 51, transfers the busy testing circuit to the lower winding of relay 48, at armature 83; connects up the wipers 88 and 91 at armatures 81 and 84; and at armature 82 transfers the operating circuit from the rotary magnet 100 to the operating lead 103 of the seized trunk. Slow acting relay 47 now de-energizes; connects up the heavy test conductors, at armatures 85 and 86; and opens the original energizing circuit of switching relay 49, at armature 76. Switching relay 49 is now maintained energized over its previously described locking circuit.

In the test connector selector F , as a result of the operation of relay 49 of switch E , the release relay 115 is energized over the following circuit: from ground by way of the working contact of armature 59 of relay 42; holds the heavy test conductors open, at armature 85 and 86; and its working contact, wiper 91; bank contact 97; conductor 105, and relay 115 to relay 46 the line relay 43 in falling back battery. Upon energizing, relay 115 opens a point in the circuit of the release magnet 120, at the same time placing ground on conductor 104 by way of the respective resting contacts of armatures 130 and 126 and the resting contact, and thence by way of pre-said armatures. By means of this ground potential on bank contact 96, and its multiples in the banks of the other test distributors, the seized trunk line is made busy to the switches having access to it.

Returning now to relay 40, its circuit was opened by the deenergization of busy relay 48, as previously stated. Relay 40, upon deenergizing, reverses the conductors 34 and 35 back to normal whereupon electropolar 70 L^4 becomes extinguished. The wire chief, upon noting that lamp L^4 has become extinguished, knows that the called trunk has become idle and accordingly

operates the key K thereby reinserting his calling device and head set into the operating circuit. The circuit conditions are now precisely the same as they would have been 80 to normal, thereby removing his calling device and head set from the operating circuit, after which he may proceed to perform his other duties.

The wire chief may now operate his calling device in accordance with the third digit of the desired number, whereupon the line relay 43 of the test distributor E , upon falling back, operates the slow acting relay 46 over a previously traced circuit. It may be stated that, while relay 42 is connected in series with line relay 43 and consequently 90 does not fall-back so promptly as line relay 43. However, the said relay 42 may, and usually does, fall-back before relay 46 has energized thereby opening the circuit of release relay 115 of switch F . The circuit of a locking circuit for itself, at armature 51, relay 115 is closed again, however, immediately, at armature 73 of relay 46 when the latter pulls up; therefore only a very short interruption is produced in the circuit of relay 115. Relay 115, if allowed to fall-back at this time, would close a circuit for the release magnet 120 and the switch shaft would be released, but, owing to the small amount of pressure exerted by the one armature 85 and 86; and opens the original energizing circuit of switching relay 49, at armature 76. Switching relay 49 is now maintained energized over its previously described locking circuit.

In addition to closing a circuit for relay 115 of switch F , at armature 73, as previously explained, closes the usual energizing circuit for relay 47 which energizes and holds the heavy test conductors open, at armature 85 and 86. In addition to operating the slow acting contact 97; conductor 105, and relay 115 to relay 46 the line relay 43 in falling back battery. Upon energizing, relay 115 opens a point in the circuit of the release magnet 120, to the rotary magnet 119 of the test connector at the same time placing ground on conductor 104 by way of the following circuit: from ground by way of armature 60 and its contacts of armatures 130 and 126 and the resting contact, and thence by way of pre-said armatures. By means of this ground potential on bank contact 96, and its multiples in the banks of the other test distributors, the seized trunk line is made busy to the switches having access to it.

Returning now to relay 40, its circuit was opened by the deenergization of busy relay 48, as previously stated. Relay 40, upon deenergizing, reverses the conductors 34 and 35 back to normal whereupon electropolar 70 L^4 becomes extinguished. The wire chief, upon noting that lamp L^4 has become extinguished, knows that the called trunk has become idle and accordingly

operates the key K thereby reinserting his calling device and head set into the operating circuit. The circuit conditions are now precisely the same as they would have been 80 to normal, thereby removing his calling device and head set from the operating circuit, after which he may proceed to perform his other duties.

trolled by armature 123, relay 117, and rotary magnet 119 to battery. By the operation of the rotary magnet, the shaft and wipers are stepped around step by step until the latter finally come to rest upon the desired set of bank contacts, assumed in this case to be the contacts 137 to 141, inclusive. Relay 117 is energized in series with the rotary magnet and being slow acting retains its armatures attracted throughout the rotary movement. Upon energizing, relay 117 shifts conductor 104, at armature 126, from ground by way of its resting contact to direct ground by way of its working contact; closes a circuit for the upper winding of relay 118 at armature 125; and, at armature 124, serves to maintain the circuit of the rotary magnet 119 intact after the energization of relay 116 which occurs upon the first step of the switch, the said relay being energized in series with the release magnet 120 which, on account of its comparatively small number of turns and the high resistance of relay 116 is not energized at this time. Relay 118, upon energizing, opens the heavy test conductors at armatures 127 and 131; disconnects wipers 133 and 134; at armatures 147 and 128, respectively; and prepares a locking circuit for itself at armature 129. At the end of the rotary movement the slow acting relay 117 deenergizes and, at armature 124, shifts the operating circuit from the rotary magnet 119 to the operating lead which extends to the resting contacts of armature 147; opens the original energizing circuit of relay 118 at armature 125; and at armature 126 extends the conductor 104 to battery by way of the resistance R^3 .

From this point the operation depends upon whether the test connector H is busy or idle. Assuming first that it is busy, in which event test contact 140 will be grounded, relay 118 remains energized, and busy relay 48 in the switch E, the lower winding of which is now connected to conductor 104, is energized in series with resistances R^3 and, upon energizing, gives the calling wire chief the before mentioned visual and audible busy signals. The calling wire chief, upon noting the before mentioned busy signals, may release the connection and call again later, but we shall assume that he decides to wait until the test connector H becomes idle.

A question may now arise in the minds of some as to whether or not another test distributor which lands on a multiple of the bank contacts 93-98, inclusive, will be given a busy signal and denied connection, in view of the fact that direct ground is now removed from conductor 104 and battery by way of resistance R^3 placed thereon. In answer to this question it may be said that the resistances of the lower winding of relay 48 and of R^3 are so proportioned as to allow the multiples of test contact 96 to remain

sufficiently near a ground potential to cause the trunk line extending to switch F to test busy at this time to the other test distributors having access to it.

We shall now assume that the test connector H becomes idle. When the ground potential disappears from conductor 140, relay 118 deenergizes, somewhat slowly so as to give connector H time to restore itself to normal condition, and at armatures 127 and 131 connects up the heavy test conductors; connects up the wipers 133 and 134 at armatures 147 and 128; places ground on test contact 140, at armature 129; and, at armature 130, removes battery from conductor 104 and places ground thereon. In the test distributor E, busy relay 48 deenergizes as soon as the resistance R is disconnected from conductor 104 thereby removing the before mentioned visual and audible busy signals, and the wire chief is apprised thereby that he may continue the operation.

Assuming now that the test connector H is idle when called as hereinbefore explained, relay 117 deenergizes at the end of the rotary movement and opens the circuit of relay 118 which deenergizes with the previously described results. It may be stated that, while relay 118 is slightly slow in falling back so as to give the test connector H time to restore to normal, as previously pointed out, it is not slow enough to give a momentary false busy to the calling wire chief.

The wire chief may now operate his calling device in accordance with the next digit of the desired number, whereupon a corresponding number of impulses are sent from ground, by way of previously traced circuit, to conductor 103 and from thence, by way of the working contact of armature 123 and said armature, armature 124 and its resting contact, resting contact of armature 147 and said armature, wiper 133, bank contact 138, off normal springs 165 and 168, relay 156 and vertical magnet 158 to battery. By the operation of the vertical magnet the shaft and wipers of the test connector H are raised step by step until the latter stand opposite the desired level of contacts, being in this case the level in which the line of substation A terminates. Slow acting relay 156 is energized in series with the vertical magnet and serves to maintain the circuit of the latter intact after the off normal springs have shifted, as they do upon the first vertical step. At the end of the vertical movement, slow acting relay 156 deenergizes and transfers the operating circuit from the vertical to the rotary magnet.

The calling wire chief may now manipulate his calling device in accordance with the next and last digit of the desired number, whereupon the rotary magnet 159 of switch H is energized a corresponding num-

ber of times. By the operation of the rotary magnet, the wipers 166 to 168, inclusive, are stepped around step by step until they finally come to rest upon the bank contacts 169 to 171, inclusive, which are the ones in which the line of substation A terminates.

The operation now depends upon whether the called line is busy or idle. If it is 19 busy there is a ground potential upon test contact 170 and slow acting relay 46 in switch E, upon falling back, completes the following circuit for reversing relay 40: from ground by way of test contact 170, 20 test wiper 167, conductor 144, bank contact 139, wiper 134, armature 128 and its resting contact, conductor 102, bank contact 94, 25 wiper 88, armature 81 and its working contact, working contact of armature 74 and 30 said armature, armature 71 and its resting contact, and reversing relay 40 to battery. Relay 40 energizes and an instant later slow acting relay 47 deenergizes. By the combined operation of relays 40 and 47, the circuit of relay 40 is shifted so as to include the normally closed contacts controlled by armature 74, and armature 55 and its working contact instead of the working contact of armature 74 and the said armature. As 35 a further result of the energization of relay 40, the calling wire chief is given the usual visual busy signal and is apprised thereby that the line of substation A is in use.

It will be noted that no audible busy 35 signal is given to the calling wire chief at this time. This, however, is not necessary for the heavy test conductors are connected with the called line at this time whether it is idle or not and the wire chief need only 40 operate the key K⁴ to connect his head set with the heavy test conductors and he may listen in and thereby ascertain the condition of the called line. In this case, as before, when a line is called and found to 45 be busy the wire chief may wait until it becomes idle when the visual busy signal is automatically extinguished.

Assuming that the line of substation A 50 is idle when called or, which is practically the same thing, becomes so after being called, relay 40 deenergizes, slightly sluggishly because of the copper slug, when the ground potential is removed from test contact 170, thereby removing the visual 55 busy signal in a manner hereinbefore described. With relay 40 deenergized a circuit may be traced from ground, by way of the working contact of armature 58 and said armature, resting contact of armature 55 and said armature, and back over the 60 previously traced circuit to test contact 170, and from thence, by way of private normal conductor 173, switching relay 180, and stepping magnet 182 to battery. It may be explained at this point that while relay

40 is slow acting it is only slightly so and that the reason for its being slow, is to allow a predetermined time, sufficient to take care of differences in adjustment, for the switching relay of the called line switch 70 to fall back before the above traced circuit is closed for it by the falling back at the said relay 40. Switching relay 180 now energizes but the stepping magnet 182 is not energized on account of the high resistance of the said switching relay. Upon energizing, switching relay 180 removes the bridge of the line relay 181 from the called line but, on account of a mechanical interlocking device (not shown) between the 80 armatures of the said relay and line relay 181, the armatures of relay 180 are operated only about half way and consequently the wipers of the line switch are not connected up. 85

Having finished dialling, the wire chief returns the key K to normal position. It will be noted that the heavy test conductors 30 and 31 normally extend to the volt meter V. The wire chief by observing the reading of the volt meter is able to determine to some extent the condition of the called line. It is understood, of course, that the keys K⁴ and K⁵, together with the impedances 37 and 38, are only a small part of the equipment that is actually provided for use in testing a line. However, the equipment shown is all that is necessary to make the present invention perfectly clear. With the 90 understanding that he has other equipment than that shown, we shall assume that the wire chief makes the necessary tests.

We shall assume now that there is a repair man at the substation A making some necessary repairs and that the wire chief wishes to co-operate with him. In order to signal the repair man at substation A, the wire chief throws key K⁵ in such a direction as to project ringing current out over the heavy test conductors, thereby operating the bridged bell at the said substation. The key K⁵ is now thrown in the opposite direction and springs 24 to 26, inclusive, are accordingly operated. The wire chief now operates key K⁴, thereby placing his head set in multiple with the heavy test conductors. 110 115

When the repair man at substation A answers, he may converse with the wire chief, talking battery being supplied to the transmitter at the called substation by way of impedances 37 and 38 and springs 24 and 26 and their working contacts. It will be noticed that with spring 24 operated the condenser 29 is in series with the wire chief's head set so as to insulate the latter from the direct current which is flowing out to the transmitter at substation A. 120 125

Assuming now that the repair man says that he has a few more repairs to make which will require only a short time, and that the 130

wire chief decides to hold up the connection while he uses his common test and operating circuits elsewhere, he operates the holding key K^2 . Upon operating, key K^2 places a multiple ground on the common conductor 36 at its lower pair of contacts; prepares a circuit for the lamp L at the adjacent pair of contacts; and closes a circuit for switching relay 20 at its upper pair of contacts. 10 Switching relay 20, upon energizing, closes a multiple bridge across the operating conductors 34 and 35 at armature 22, and at armatures 21 and 23 disconnects the heavy test conductors from the wire chief's test circuit and connects them to the upper and lower windings of relay 16. The wire chief may now return the key K^3 to normal and use the test circuit for testing other lines while he is waiting for the repair man to signal that 15 he is ready for line of substation A to be tested.

It will be noted that the key K^3 , upon returning to normal position, lights the busy lamp L^2 since there is a ground potential 20 on conductor 36 independent of the said key K^3 .

After the repair man has made the necessary repairs and is ready to signal the wire chief, he lifts the receiver at substation A 25 from the hook, thereby closing a circuit for relay 16, Fig. 1, which, upon operating, closes a circuit for the lamp L at armature 17. The wire chief upon noting the lighted condition of lamp L knows that the repair 30 man desires to converse with him. Accordingly he reoperates the key K^3 and operates keys K^5 and K^4 so as to connect his head set in bridge of the test conductors and place 35 talking battery on the said conductors by way of impedances 37 and 38. The wire chief now restores the key K^2 to normal position, whereupon the lamp L is extinguished and relays 16 and 20 are deenergized, and the heavy test conductors are connected up 40 again at armatures 21 and 23. Obviously the wire chief and repair man may now converse as before.

We shall now assume that the wire chief wishes to test the line switch C to find out 45 whether or not the said switch is functioning properly. In order to do this the wire chief returns the key K^5 to normal position thereupon removing the impedances 37 and 38 from in bridge of the test conductors 30 and 31 and replacing the short-circuit around condenser 29 at spring 24. The wire chief now operates the key K' in such a direction 50 as to separate the spring 5 from its resting contact, thereby introducing the resistance 55 R into the operating circuit.

In the test distributor E, relay 41, being marginally adjusted, falls back when the said resistance is introduced into its circuit but relays 42 and 43 do not deener- 60 gize at this time. Upon deenergizing, re-

lay 41 opens the circuit of switching relay 180 of the line switch C and the said relay deenergizes. Upon deenergizing, switching relay 180 connects the line relay 181 in bridge of the line conductors 172 and 174. Upon energizing, over the heavy test conductors in series with the wire chief's head set, line relay 181 closes at armature 187 a circuit for the switching relay 180 and the stepping magnet 182 in series, and at armature 186 connects the test wiper 189 to the above circuit at a point between the switching relay and the stepping magnet. The operation now depends upon whether the trunk line upon which the wipers of the line switch are standing is busy or idle. If it is busy, the test contact with which the test wiper 189 is in engagement is grounded, switching relay 180 is short circuited; and the stepping magnet 182 which interrupts its own circuit is operated in the manner of a buzzer to advance the wipers step by step in search of an idle trunk line. In the present case, however, we may assume that 80 the trunk line upon which the wipers of the line switch are standing is idle. That being the case, the stepping magnet 182 is not energized because of the high resistance of the switching relay, but the latter is energized, grounds the test wiper at armature 185; disconnects the line conductors 172 and 174 from the winding of line relay 181 and from ground respectively, and extends them by way of line wipers 188 and 190 to the upper and lower winding of the line relay of a first selector switch. The line and release relays (not shown) of the 85 said selector immediately energize and the latter places ground on the release trunk conductor thereby establishing the usual holding circuit for the switching relay 180. It is obvious that the wire chief may return the key K' to normal any time after the line relay 181 has operated. From this 90 point the operation may proceed in any one of a number of ways, for example, the wire chief may have a telephone at his desk, and, assuming he has, he may call the number of said telephone and in that way find out whether or not he is able to operate the exchange switches from the line in question.

We shall now assume that the wire chief desires to test the line of a substation which terminates in the same level as the line of substation A and in a set of contacts that is farther around in the rotary movement of the switch than the set in which the line of substation A terminates, for example, the line of substation A may terminate in the fifth set of contacts in the level. Now, in case the wire chief desires to test another line which terminates in the sixth, or any of the following sets in the same level, he may operate his calling device in accordance 100 105 110 115 120 125 130

with the proper digit and thereby cause the rotary magnet 159 of the connector H to step the wipers 166 to 168, inclusive, around to the desired set of contacts, the operation 5 in this case being the same as that when the last digit of the number of substation A is called.

We shall now assume that the wire chief desires to test a line which terminates in 10 the banks of the connector H, either in a different level from that in which the line of substation A terminates or in the same level but in a set of contacts that has already been passed over by the switch wipers.

15 In order to release the test connector selector F and the test connector H without releasing the test distributor E, the wire chief operates the key K' in such a direction as to separate the spring 6 from its resting 20 contact, thereby introducing the resistance R' into the operating circuit. In the test distributor E, relays 41 and 42 fall back when the said resistance is introduced into their circuit, relay 42 also being marginally 25 adjusted, but line relay 43 does not deenergize at this time. Relay 41, upon deenergizing, removes ground from the wipers 184 and 167 at armature 58, so that they will not interfere with the contacts over 30 which they pass. Relay 42, upon deenergizing, opens the circuit of release relay 115 of selector F at armature 59. Upon deenergizing, release relay 115 opens the circuit of release relay 155 of connector H and 35 at the same time closes a circuit for release magnet 120. By the operation of the release magnet the shaft and wipers of switch F are restored to normal position, the circuit of the release magnet being opened at off normal contacts 122 by the shaft when it reaches normal position. Obviously the relay 116 deenergizes as a consequence of the above operation.

40 In the connector H, release relay 155, upon deenergizing, closes the circuit of release magnet 157, which energizes and restores the switch to normal position in the usual manner. It is to be understood that the wire chief may release the test distributor also by throwing the key K to release position, for in this position spring 4 completely 45 opens the circuit of relays 41-43, inclusive, of switch E.

45 The wire chief now restores the key K' to normal position, thereby short circuiting the resistance R' and allowing relays 41 and 42 to energize again. He may now operate his calling device in accordance with the proper digits and thereby cause the selector F and 50 the connector H to operate again to give access to any line that terminates in the banks of the said connector. It is obvious that in case the wire chief desires to test a line that terminates in the banks of another connector to which the selector F has

access, he could do so equally well without releasing the test distributor E.

Having finished making the necessary tests, the wire chief returns the key K' to normal position, thereby removing ground from the common conductor 36 whereupon the busy lamps in front of the other wire chiefs become extinguished and the trunk line is rendered idle to the automatic switches having access to it. As a further result of the operation of the key K' the wire chief's test and operating conductors are disconnected from the test and operating conductors of the trunk line, whereupon, the relays 41-43, inclusive, deenergize. Relay 43, upon deenergizing, opens the circuit of release relay 44 at the same time placing ground upon the operating conductor extending to the switches ahead, thereby operating the test connector to cause it to step around another step. This, however, has no particular utility at this time. In addition to operating the test connector as explained, this ground on the operating conductor operates slow acting relay 46 in the usual manner. Relay 46, upon energizing, closes the circuit of release relay 115 of switch F, thereby preventing its deenergization as hereinbefore explained. Slow acting relay 47 is energized at this time in the usual manner, but its energization has no particular function during this operation. Slow acting release relay 44 now falls back, thereby removing ground from the operating conductor extending to the connector H, whereupon the rotary magnet of the said connector deenergizes. Slow acting relay 46, however, holds up for a moment. As a further result of the deenergization of relay 44, it opens, at armature 61, the circuit of the slow acting relay 47 and switching relay 49. Slow acting relay 47 holds up for a moment but switching relay 49 deenergizes and, at armature 84, opens the circuit of release relay 115 of switch F. The switches F and H now release in the usual manner.

55 Returning now to release relay 44, as a still further result of its deenergization, it closes, at armature 62, a circuit for the release magnet 64. By the operation of the release magnet, the shaft and wipers are restored to normal position, the circuit of the release magnet being opened at off normal contacts 67 by the shaft when it reaches normal position. Slow acting relays 46 and 47 now fall back. All of the apparatus used by the wire chief in making the tests is now restored to normal position.

60 It may be stated now that, in case the wire chief calls a line that terminates in a so called straight line board or a board in which there is only one group of connectors, the calling wire chief need only omit the digit used in the previously described case 65 125 130

to operate the test connector selector F. This is perfectly obvious in view of the fact that the trunk extending to the test connector in such a case is terminated directly in the banks of the test distributors.

Attention is now called to the fact that, while there are six conductors in the trunk line leading to the test connector H, there are only five wipers on the switch F and consequently only five bank contacts in each set. This is due to the fact that the wiper 135 of switch F, which corresponds to wiper 91 of switch E, is used not only to send a ground potential ahead, to operate the release relay of the next switch, but also as a test wiper. That being the case, conductor 148 has no utility whatever when the connector H is used in a party line board, but when the said connector is used in a straight line board the said conductor 148 terminates in test contacts in the banks of the test distributors corresponding to the test contact 96 in the bank of the test distributor E.

25 We shall now assume that a complaint, or verification operator, whose head set is shown in Fig. 4, desires to call the line of substation A to find out whether it is busy, idle, or out of order. This is done, usually, only after someone has called in to the said operator and made a complaint concerning the said substation. In order to initiate such a call, the complaint operator throws a key associated with an idle trunk line, the key K⁷ for example, the associated trunk line being idle as denoted by the unlighted condition of the lamp L⁴. Upon operating, key K⁷ closes, at spring 262, a circuit for the busy lamp L³ and its multiples in front of the other operators, but does not close a circuit for the busy lamp L⁴ owing to the fact that the circuit of the said lamp is opened by spring 262, at this time. As a further result of the operation of key K⁷, it closes a circuit for the right-hand or polarizing winding of the electropolarized relay 200, at spring 261. It is to be understood that relay 200 is an exact duplicate of the electropolarized relay 7, Fig. 1, which has been previously described. Accordingly, relay 200 is not operatively energized by this winding alone. As a still further result of the operation of key K⁷, it places a bridge across the conductors 250 and 251 of the trunk line, at springs 260 and 263, including the left hand winding of electropolarized relay 200, the secondary windings of the operator's induction coil, the associated resistance, and the impulse springs of the calling device S². The conductors 250 and 251 extend, by way of the normally closed contacts controlled by armatures 213 and 214, to the upper and lower windings of line relay 203 of the test distributor selector repeater D. The upper winding of line relay 203 is connected to

battery, while the lower winding extends to ground, by way of the normally closed contacts controlled by spring 211, and accordingly the said relay energizes. Electropolarized relay 200, however, associated with the operator's head set, is not energized at this time, owing to the fact that the current flowing in its left-hand winding is in a direction opposite to that in which it must flow in order to energize the said relay. Line relay 203, upon energizing, closes a circuit for the release relay 205, which, upon energizing, opens a point in the circuit of the release magnet 224 and closes a point in the circuit of the vertical magnet 222 at armature 220; and at armature 219 closes a circuit for the left hand or polarizing winding of electropolarized relay 201. This relay also is identical with relay 7, Fig. 1, and accordingly does not operate at this time.

The operator may now manipulate her calling device S² in accordance with the first digit of the desired number whereupon the line relay 203 is deenergized a corresponding number of times and, upon each deenergization, completes the following circuit: from ground by way of armature 216 and its resting contact, armature 220 and its working contact, slow acting series relay 206, resting contact of armature 231 and said armature, and vertical magnet 222 to battery. By the operation of the vertical magnet, the shaft and wipers are raised step by step until the latter stand opposite the desired level of bank contacts, assumed in this case to be the level in which the trunk line comprising conductors 32-36, inclusive, terminates. Relay 206 is energized in series with the vertical magnet and being slow acting retains its armatures attracted throughout the vertical movement. By the joint operation of armature 221 and the off normal contacts 226, which close upon the first vertical step, a circuit is closed for the stepping relay 207. Upon energizing, relay 307 prepares a circuit for the rotary magnet 223 at armature 227 and at armature 228 establishes the following locking circuit for itself: from ground by way of the resting contact of armature 252 and the said armature, working contact of armature 228 and said armature, resting contact of the armature of rotary magnet 223 and said armature, off normal contacts 226, and stepping relay 207 to battery. At the end of the vertical movement, relay 206 deenergizes and closes the circuit of rotary magnet 223. Upon energizing, magnet 223 steps the wipers 240 to 244, inclusive, into engagement with the first set of contacts in the level opposite which they are raised, at the same time opening the previously described locking circuit of stepping relay 207. Relay 207 accordingly deenergizes and at armature 227 opens the circuit of the rotary magnet which

deenergizes also and closes its interrupter contacts again.

The operation now depends upon whether the trunk line terminating in the first set of contacts is busy or idle. If it is busy test wiper 242 engages a grounded contact and the stepping relay 207 energizes again. This same cycle of operation is repeated over and over until an idle or ungrounded 10 test contact is reached. Assuming that all the trunk lines terminating in the called level are busy, this alternate operation of the rotary magnet and stepping relay continues until the wipers 240-244, inclusive, 15 pass off the last set of contacts. The cam 212 is so placed and adjusted as to operate the springs 209-211, inclusive, whenever the shaft is rotated sufficiently to cause the wipers to pass off the last set of contacts 20 in the level. Spring 209, upon operating, opens the circuit of the switching relay 204 so as to prevent its energization at this time. Spring 210 upon operating closes a circuit for reversing relay 202 and the said reversing 25 relay, upon energizing, reverses the line conductors 250 and 251 as regards their connection with the windings of line relay 203. This obviously reverses the flow of current in the said conductors and in the left hand winding of the electropolarized relay 200. Relay 200 energizes now and closes a circuit 30 for the busy lamp L^2 .

Returning now to the operation of the springs 209-211, inclusive, the spring 211 upon operating shifts the circuit of the lower winding of line relay 203 so as to include the left hand winding of the transformer associated with the busy signalling machine B'. As a result of this operation, 35 the operator is given an audible busy signal in addition to the visual busy signal already described. Upon noting the busy signals, the operator may release the connection and call again later.

45 In the present case, however, we shall assume that all the trunk lines terminating that level are not busy and that the trunk line terminating in bank contacts 245-249, inclusive, is the first one found idle. That 50 being the case, when the wipers 240-244, inclusive, arrive upon the said contacts the switching relay 204, being no longer short circuited, energizes over the following circuit: from ground by way of armature 219 and its working contact, resting contact of 55 spring 209 and said spring, switching relay 204, resting contact of the armature of rotary magnet 223 and said armature, off normal contacts 226, and stepping relay 207, to battery. Stepping relay 207 is not energized at this time, however, on account of 60 its comparatively small number of turns and stiff adjustment. Upon energizing, relay 204 grounds the test wiper 242 at armature 217 so as to make the seized trunk

busy; opens a point in the circuit of the vertical magnet 222, at armature 231; removes ground from the locking circuit of stepping relay 207 at armature 252; and at armature 218 places the following bridge 70 across the operating conductors 34 and 35 of the seized trunk line: from conductor 35, by way of bank contact 248, wiper 243, armature 218 and its working contact, working contact of armature 215 and said armature, 75 right hand winding of electro-polarized relay 201, wiper 241, and bank contact 246, to conductor 34. Relays 41-48, inclusive, in the test distributor E now energize and prepare the switch for operation in the 80 usual manner. Electropolarized relay 201, however, does not energize at this time owing to the fact that the current is flowing in its right hand winding in the direction opposite to that in which it must flow in 85 order to operate the said relay. It will be noted that busy lamp L^2 , as well as its multiples in front of the other wire chiefs, is lighted at this time to inform them of the 90 busy condition of the trunk line.

95 The operator may now operate her calling device S^2 in accordance with the remaining digits of the desired number, whereupon the line relay 203 of selector D is deenergized a corresponding number of times; and, at each deenergization, opens the circuit of line relay 43 of the test distributor E at armature 215. It is obvious that the test distributor E, as well as the switches F and H, operates in the same manner in this call 100 as it does when the wire chief makes a call, such as the one previously described. In case a busy signalling current is placed on conductor 35 by the test distributor E, it flows back by way of armature 218 of switch 105 D and its working contact, and condenser 264 to the lower winding of line relay 203, and thence to the calling operator's head set. In response to any reversal of current 110 in conductors 35 and 36, the electropolarized relay 201 operates and closes the circuit of reversing relay 202, thereby, finally giving the calling operator a visual busy signal, as hereinbefore described.

115 After having called the number, the operator is able to ascertain, by listening in, whether or not the line of substation A is busy; and, after obtaining the desired information, she restores the key K^7 to normal position, thereby opening the circuit of 120 the line relay 203 which, upon deenergizing, opens the circuit of release relay 205. Relay 205, upon deenergizing, opens the circuit of switching relay 204 at armature 219. Relay 204, upon deenergizing, opens the 125 bridge across the operating conductors at armature 218 whereupon the switches E, F, and H restore to normal position, in the usual manner. As a further result of the 130 operation of release relay 205, it closes the

circuit of release magnet 224. By the operation of the release magnet the shaft and wipers are restored to normal position, the circuit of the said magnet being broken at 5 off normal contacts 225 by the shaft, when it reaches normal position.

Having described my invention, what I consider to be new and desire to have protected by Letters Patent will be pointed out 10 in the appended claims.

What I claim as my invention is:

1. In a wire chief's testing system, a testing circuit comprising apparatus for testing subscribers' lines, a series of automatic switches controlled from said test circuit to connect the same with a subscriber's line, a marginal relay for controlling the release of one of said switches, a control circuit including said relay controlled by the 15 wire chief, and means in said control circuit for preventing the release of another of said switches.

2. In a wire chief's testing system, a testing circuit comprising apparatus for testing 25 subscribers' lines, a series of automatic switches controlled from said test circuit to connect the same with a subscriber's line, a marginal relay in the first one of said switches for controlling the release of all the 30 rest of said switches, another relay for controlling the release of the said first switch, and means in the said test circuit for controlling said relays separately.

3. In a wire chief's testing system, a testing 35 circuit comprising apparatus for testing subscribers' lines, a series of automatic switches controlled from said test circuit to connect the same with a subscriber's line, a relay in one of said switches for controlling the release thereof, a marginal relay for 40 controlling the release of the rest of said switches, a common circuit including both relays, and means in the said test circuit for altering the current flow in said circuit to 45 cause the deenergization of one relay independent of the other.

4. In a wire chief's testing system, a testing 50 circuit comprising apparatus for testing subscribers' lines, a series of automatic switches controlled from said test circuit to connect the same with a subscriber's line, a relay in one of said switches for controlling the release thereof, a marginal relay for controlling the release of the final switch, a 55 common circuit including both relays, and means in said test circuit for reducing the current flow in said circuit enough to de-energize the said marginal relay while maintaining the other relay energized.

5. In a wire chief's testing system, a 60 series of automatic switches for connecting a test circuit at the wire chief's desk with a subscriber's line to be tested, a line relay and a marginal relay in one of said switches,

a circuit including both relays, means at the 65 wire chief's desk for varying the current in said circuit to control one of said relays independently of the other, and release means in two of said switches controlled by said relays, respectively. 70

6. In a wire chief's testing system, a series of automatic switches for connecting a test circuit at the wire chief's desk with a subscriber's line to be tested, a line relay and a marginal relay in one of said switches, 75 a circuit including both relays, means at the wire chief's desk for varying the current in said circuit to control one of said relays independently of the other, releasing means for the final switch controlled by said marginal relay, and releasing means for another switch controlled by said line relay.

7. In a wire chief's testing system, a series of automatic switches for connecting a test circuit at the wire chief's desk with a subscriber's line to be tested, a circuit for energizing the cut-off relay of the subscriber's line when the line is connected with, a marginal relay in one of said switches for closing said circuit, a line relay in the same switch, a common circuit including both relays, and means at the wire chief's desk for varying the current in said common circuit to control said marginal relay independently of said line relay. 95

8. In a wire chief's testing system, a series of automatic switches for connecting a test circuit at the wire chief's desk with a subscriber's line to be tested, a circuit for energizing the cut-off relay of the subscriber's line when the line is connected with, a marginal relay in one of said switches for closing said circuit, a line relay in the same switch, a common circuit including both relays, and means at the wire chief's desk for reducing the current flow in said common circuit to deenergize the said marginal relay independent of said line relay. 100

9. In a wire chief's testing system, a series of automatic switches for connecting a test circuit at the wire chief's desk with a subscriber's line to be tested, a line relay and two marginal relays in one of said switches, a circuit controlled by one of said marginal relays for energizing the cut-off relay of the subscriber's line when the line is connected with, releasing means in the final switch controlled by the other of said marginal relays, a common circuit including said line relay and both marginal relays, and means at the wire chief's desk for varying the current in said common circuit to cause one or both of said marginal relays to deenergize independent of said line relay. 110

10. In a telephone system, a trunk line 125 including two talking conductors, two serially related automatic switches for connecting said trunk line with a called sub-

scriber's line, primary and secondary operating magnets in the final switch, only two relays in the final switch, one controlling the release of said switch and the other controlling the change over from primary to secondary operation, and other relays in the said first switch for exercising all other nec-

essary control over the final switch, including a relay for opening the said talking conductors while the said final switch is being operated.

In witness whereof, I hereunto subscribe my name this 10th day of May, A. D. 1921.

CLARENCE E. LOMAX.
